(57) **CLAIM**

The ornamental design for a massage gun mount, as shown and described.

DESCRIPTION

FIG. 1 is a top-right perspective view of a massage gun mount showing my new design, showing the massage gun mount attached to a mobility aid and massage gun.

FIG. 2 is a top-left perspective view of the massage gun mount shown in FIG. 1 showing the massage gun mount attached to a mobility aid and a massage gun.

FIG. 3 is a top-left perspective view of the massage gun mount shown in FIG. 1.

FIG. 4 is a front elevation view of the massage gun mount shown in FIG. 1.

FIG. 5 is a back elevation view of the massage gun mount shown in FIG. 1.

FIG. 6 is a left elevation view of the massage gun mount shown in FIG. 1.

FIG. 7 is a right elevation view of the massage gun mount shown in FIG. 1.

FIG. 8 is a top plan view of the massage gun mount shown in FIG. 1.

FIG. 9 is a bottom plan view of the massage gun mount shown in FIG. 1.

FIG. 10 is a bottom-right perspective view of the massage gun mount shown in FIG. 1, where the massage gun mount is not attached to a mobility aid or a massage gun.

FIG. 11 is a back elevation view of the massage gun mount shown in FIG. 1, where the massage gun mount is not attached to a mobility aid or a massage gun.

FIG. 12 is a front elevation view of the massage gun mount shown in FIG. 1, where the massage gun mount is not attached to a mobility aid or a massage gun.

FIG. 13 is a right elevation view of the massage gun mount shown in FIG. 1, where the massage gun mount is not attached to a mobility aid or a massage gun.

FIG. 14 is a left elevation view of the massage gun mount shown in FIG. 1, where the massage gun mount is not attached to a mobility aid or a massage gun; and,

(Continued)

FIG. 15 is a bottom plan view of the massage gun mount shown in FIG. 1, where the massage gun mount is not attached to a mobility aid or a massage gun. The broken lines in the drawings depict environmental structure of the massage gun mount that form no part of the claimed design.
